DESCRIPTION

FIG. 1 is a front view;

FIG. 2 is a rear view;

FIG. 3 is a left-side view;

FIG. 4 is a right-side view;

FIG. 5 is a perspective view;

FIG. 6 is a reference front view with cross sectional line indicators; and,

FIG. 7 is an enlarged cross-section view taken along the line A—A in FIG. 6.

In the drawings, the broken lines defining the sidewall, inner bead and the peripheral boundary between the claimed tire tread and the unclaimed sidewall depict environmental subject matter that forms no part of the claimed design.
